UTILITY CART FOR THE COLLECTION AND DELIVERY OF LAUNDRY AND DRY CLEANING

Thomas Noble Vaughan, Sr., 117 Henry Clay Road,
Ashland, Va.

Filed Dec. 10, 1964, Ser. No. 82,980

Term of patent 14 years

(Cl. D14—3)

FIG. 1.

FIG. 2.

FIG. 3.

FIG. 4.

FIG. 5.

FIG. 1 is a front perspective view of a utility cart for the collection and delivery of laundry and dry cleaning, showing my new design;

FIG. 2 is a fragmentary perspective view thereof, the receiving chute and the doors to the soiled laundry compartment being in an open position;

FIG. 3 is a rear elevational view thereof, the chute to the soiled laundry compartment being in an open position; and

FIGS. 4 and 5 are end elevational views taken from the right and left, respectively, of FIG. 1.

The broken line representation of packages of clean laundry and finished dry cleaning in FIG. 3 are for purposes of illustration only.

This is a continuation-in-part of application Serial No. D. 77,860, filed December 19, 1963, now abandoned.

I claim:

The ornamental design for a utility cart for the collection and delivery of laundry and dry cleaning, substantially as shown and described.
